(57) **CLAIM**

The ornamental design for a foldable transaction card case, as shown and described.

DESCRIPTION

FIG. 1 is a top perspective view of a foldable transaction card case showing our new design;

FIG. 2 is a bottom perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a top plan view thereof; and,

FIG. 8 is a bottom plan view thereof.

The broken line showing of a key ring, in the views, is for illustrative purposes only and forms no part of the claimed design.
